HAND PULLED SHOVEL

Lorenz H. Kutz, Rte. 1, Mound, Minn. 55364

Filed Feb. 2, 1968, Ser. No. 10,423

Term of patent 14 years

(Cl. D39—1)

FIG 1

FIG 2

FIG 3

FIG 4

FIG 5

FIG 6

FIGURE 1 is a perspective view of the hand pulled shovel with the handle broken away to indicate indeterminate length.

FIGURE 2 is a top view of the hand pulled shovel;

FIGURE 3 is a side view of the hand pulled shovel;

FIGURE 4 is a front elevational view of the hand pulled shovel;

FIGURE 5 is a rear elevational view of the hand pulled shovel; and

FIGURE 6 is a bottom view of the hand pulled shovel. A portion of the handle has been omitted in FIGURES 2, 3 and 6 for convenience of illustration.

I claim:

The ornamental design for a hand pulled shovel, as shown and described.
